UNITED STATES PATENT OFFICE.

BENJAMIN B. HOFFMAN, OF NEW YORK, N. Y., ASSIGNOR TO JAMES H. HOFFMAN, OF SAME PLACE.

INCANDESCENT-ELECTRIC-LAMP FIXTURE.

SPECIFICATION forming part of Letters Patent No. 590,838, dated September 28, 1897.

Application filed February 6, 1897. Serial No. 622,372. (No model.)

To all whom it may concern:

Be it known that I, BENJAMIN B. HOFFMAN, a citizen of the United States, residing at New York city, in the county and State of New York, have invented a certain new and useful Improvement in Incandescent-Electric-Lamp Fixtures, of which the following is a specification.

The object of my invention is to provide a fixture for incandescent electric lamps supplied with current from a battery. In carrying my invention into effect I preferably employ a portable fixture, in the hollow base of which I place a small storage battery for supplying current. I provide the hollow base with a cover which may be hinged to the base, and upon this cover is mounted a tubular ornamental stem or arm which carries the lamp-socket and the circuit controller and terminals.

My invention is illustrated in the accompanying drawings, in which—

Figure 1 is a view illustrating the base of the fixture in section to show the position of the storage battery, the lamp-arm being shown in elevation and the cover for the base being partly broken away to show the circuit-terminals. Fig. 2 is a central vertical section of the cover and the lamp-arm on an enlarged scale, and Fig. 3 is a detail of the lamp-socket.

Referring to the drawings, A is the hollow base of the fixture containing the storage battery B.

C is a cover hinged to the base A at C' and provided with a catch or lock C². A metal tube or arm D, having a shell d, is mounted upon the cover C. This shell, as will be seen in Fig. 2, is seated upon a ring c, resting upon the upper side of the cover C, and within the cover is a disk c', provided with a central screw-threaded hole which is adapted to be screwed onto the screw-threaded end of the tube D and by means of which the tube D is rigidly held to the cover. The ring c may be dispensed with, if desired, in which case the shell d will be seated directly upon the cover. The tube D carries one of the circuit-terminals F, which is a piece of spring metal and is clamped between an insulating-washer f and a nut f', which is screwed onto the screw-

threaded end of a metal rod f², which passes through the lower end of the tube D and is provided with a flange f³, which is seated upon an insulating-washer f⁴, which in turn 55 is seated upon the flange f⁵ of the tube D. The shoulder f³ and the nut f' serve to rigidly secure the rod f² in position within the tube D and to make intimate mechanical contact between the terminal F and said rod, and the 60 insulating-washers f and f⁴ serve to insulate the terminal F and the rod f² from the tube D. The other circuit-terminal G is clamped between the cover C and the disk c', whereby it is brought into close mechanical and electrical contact with the disk, so that said disk and the tube D will form one side of the circuit to the lamp. The contacts F and G, when the cover C is closed, make contact with the terminals F' and G' of the battery, thus avoiding wire connections. The lamp E is screwed within a socket e, having a tongue e', provided with a hooked end or finger e², which registers with the screw-threaded terminal on the base of the lamp and serves to hold the 75 same in place and to make electrical contact therewith. This socket, as will be seen in Fig. 2, is a piece of tubing provided with a shell h, said socket and shell being rigidly secured to a piece of tubing h', the lower end 80 of which is screw-threaded and adapted to screw into the upper end of the tube D. Within the socket e and tube h' is a long screw i, which passes through two disks i' of insulation. These disks bear against shoulders i², 85 so that when the nut on the screw i is tightened the screw is firmly held in place and is insulated from the socket e and the tube h'. The head of the screw i is in such position within the socket e as to form the circuit-terminal, with which the contact e² of the lamp makes contact. The lower end of the screw i extends within the tube D, so that a spring-finger k may make contact therewith to close the circuit to the lamp. This spring-finger 90 95 is mounted upon the rod f² and is moved into contact with the screw i by a key or screw K when screwed into the tube D. The spring-finger k is provided with a piece of insulation k' to insulate it from the screw K.

L is a reflector carried by a spring-clip having two arms l, adapted to surround the up-

per edge of the shell *h*, so as to hold the reflector in position.

What I claim is—

1. The combination with an electric-lamp fixture having a hollow base, of a battery within the base, a cover for said base upon which is mounted the lamp-supporting stem or arm and which stem or arm forms one side of the lamp-circuit, two insulated metal rods within said stem, one for making contact with one of the lamp-terminals and the other for making contact with one of the battery-terminals, and a circuit-controller for making contact between said rods, substantially as set forth.
2. The combination of an electric-lamp fixture having a hollow base, a battery within the base having two contact-terminals, a cover for said base having a tubular lamp-supporting stem or arm mounted thereon and forming one side of the lamp-circuit, a spring-metal contact carried by said cover adapted to make contact with one terminal of the battery, a conductor within said lamp-stem but insulated therefrom and having a spring-metal contact on the exterior of the stem adapted to make contact with the other terminal of the battery, and a socket for the lamp mechanically and electrically connected with the stem and with which one terminal of the lamp makes contact, and an insulated contact within the socket with which the other terminal of the lamp makes contact, substantially as set forth.
3. The combination with an electric-lamp fixture, of a tubular lamp-supporting stem or arm, one end of said tube constituting a lamp-socket and having a bent blade or finger for engaging a collar on the lamp to hold the lamp in place, an insulated metal rod within one end of the tube and projecting into the socket and with which one of the lamp-terminals is adapted to make contact, an in-

sulated metal rod within the other end of said tube adapted to make contact with a circuit-terminal, a spring contact-maker carried by one of said rods, and a key for controlling said contact-maker, substantially as set forth.

4. The combination with an electric-lamp fixture, of a tubular lamp-supporting stem or arm made in two parts and adapted to be screwed together, one part constituting a lamp-socket having means for engaging a collar on the lamp to hold the lamp in place, and an insulated rod with which one of the lamp-terminals is adapted to make contact, and which rod extends into the second section of the stem; an insulated metal rod in said section of the stem adapted to make contact with a circuit-terminal, a spring contact-maker carried by said rod adapted to make contact with the rod in the socket portion of the stem, and a key for controlling said contact-maker, substantially as set forth.

5. The combination with an electric-lamp fixture, of a tubular lamp-supporting stem or arm, one end of said tube constituting a lamp-socket and having means for engaging a collar on the lamp to hold the lamp in place, an insulated metal rod within one end of the tube and projecting into the socket and with which one of the lamp-terminals is adapted to make contact, an insulated metal rod within the other end of said tube adapted to make contact with a circuit-terminal, a spring contact-maker carried by one of said rods, a key for controlling said contact-maker, and a reflector carried by two arms adapted to surround the lamp-stem and hold the reflector in position, substantially as set forth.

This specification signed and witnessed this 13th day of October, 1896.

BENJAMIN B. HOFFMAN.
